ATTORNEY

UNITED STATES PATENT OFFICE.

CHARLES A. BAILEY, OF CROMWELL, CONNECTICUT.

TOY PISTOL.

1,307,472.

Specification of Letters Patent. Patented June 24, 1919.

Application filed December 30, 1918. Serial No. 268,836.

To all whom it may concern:

Be it known that I, CHARLES A. BAILEY, a citizen of the United States, and a resident of Cromwell, in the county of Middlesex and 5 State of Connecticut, have invented a new and Improved Toy Pistol, of which the following is a specification.

My invention relates to the class of toys used for detonating so called "paper caps," 10 and an object of my invention, among others, is to provide such a toy that shall be extremely simple in its construction and operation.

One form of toy embodying my invention 15 and in the construction and use of which the objects herein set out, as well as others, may be attained, is illustrated in the accompanying drawings, in which—

Figure 1 is a side view of my improved 20 toy pistol.

Fig. 2 is a top plan view with parts broken away to show construction, and with the percussion plate in its retracted position.

In the accompanying drawings the number 25 5 indicates the frame of my improved pistol that may be constructed of any suitable metal, and that preferably comprises a web 6 located at one side of a plane extending vertically through the pistol lengthwise 30 thereof, a flange 7 projecting slightly beyond this web at the top and on one side thereof and a flange 8, similar to the flange 7, projecting from the opposite side of said web along the top and back to form a housing 35 for the working parts of the pistol. These working parts include a cap wheel 9 pivotally mounted on a stud 10 projecting from the inner face of the web 6. This cap wheel has recesses 11 formed about its periphery 40 to receive the paper caps.

A percussion plate 12 is slidably mounted on the frame with a detonating lip 13 at its rear end. A spring 16, preferably of U-shape, has one bent end projecting into a 45 recess 4 in the lip or hammer head 13. The U-bend in the spring passes underneath a notch in a lug 14 projecting from the web 6, and the end of the spring opposite that engaging the percussion plate 12 is bent to rest 50 with one edge at least in a notch formed in the side of a lug 15, the notches in the two lugs together with the bent ends of the spring securely holding the spring in place and the spring projecting into a recess in the 55 hammer head also supports the rear end of the percussion plate 12 and holds it in place.

In its forward position, the lip 13 is located in one of the recesses 11. The plate has an offset part 17 at its forward end terminating in a finger 18 that projects through a slot 19 in the web 6; this finger projecting forwardly and serving to hold this end of the plate in position. A trigger 20 projects from the lower edge of the plate, toward its front end, and a shield 21 also constituting a part of the plate, projects from its lower edge to at least partially cover the cap wheel 9.

A notch 22 is formed in the lower edge of the slot 19 to receive the offset part 17 of the plate and hold the latter in its rearward position. The offset part is released from the notch by pressure on the trigger 20, and when so released the spring 16 will force the plate quickly forward causing the lip 13 to strike a cap and explode it.

A detent 23 is formed on the lower edge of the shield 21, this detent extending inwardly to engage the prongs 24 forming the recesses 11 on the cap wheel. As the plate is forced 80 backwardly the detent will engage a projection and rotate the wheel one step, and in the forward movement of the plate the detent will spring outwardly and slip past the next projection on the wheel.

In accordance with the provisions of the patent statutes, I have described the principles of operation of my invention, together with the device which I now consider to represent the best embodiment thereof; but I 90 desire to have it understood that the device shown is only illustrative, and that the invention may be carried out by other means.

I claim:

1. In a toy pistol, a frame, a cap wheel 95 rotatably mounted on the frame, a plate movably mounted on the frame and on the opposite side of the wheel from the frame, said plate having a detonating lip positioned to strike caps on the cap wheel, and means 100 for temporarily holding the plate in its rearward position.

2. In a toy pistol, a frame having a recess opening to one side, a cap wheel rotatably mounted in said recess, a plate movably mounted on the frame and forming a cover for said recess, said plate having a detonating lip positioned to strike caps on the cap wheel, and means for temporarily holding the plate in its rearward position.

3. In a toy pistol, a frame, a cap wheel rotatably mounted on the frame, a plate

movably mounted on the frame and slidably secured thereto at its upper end, said plate having a detonating lip positioned to strike caps on the cap wheel, and a spring attached 5 to the frame and to said plate to support the latter at its rear end.

4. A cap holding wheel turning on a central axis, in combination with a slidably mounted detonating plate having a lip to 10 strike into cap pockets in said wheel, together with suitable mechanical means connecting said plate and wheel to move the

latter one space as the slide is forced back and released for forward stroke to detonate a paper cap.

5. In a toy pistol, a frame, a cap wheel rotatably mounted on the frame, and a plate movably mounted on the frame on the opposite side of the wheel therefrom and comprising a member of the firing mechanism, 20 said plate also comprising a holder to retain said wheel in the frame.

CHARLES A. BAILEY.
